(57) **ABSTRACT**

A system and method for implementing a secondary lottery game with a first instant lottery game in an instant lottery game ticket is disclosed. The player purchases an instant lottery game, where chances for winning instant prizes are provided to the player. The player may also be provided a chance to win entry with predetermined entry indicia into a secondary lottery game if the instant lottery ticket indicates that the player has won a ticket to the secondary lottery game.

COMBINATION SCRATCH TICKET AND
ON-LINE GAME TICKETCROSS-REFERENCE TO RELATED
APPLICATION

This application claims the benefit of U.S. Provisional Application No. 60/681,752, Combination Scratch Ticket And On-line Game Ticket, filed on May 17, 2005, the specification of which is hereby incorporated in its entirety by this reference.

BACKGROUND OF THE INVENTION

1. Field of the Invention

The invention relates in general to lottery and promotional tickets or games, and more particularly to an instant win scratch-off lottery or promotional game ticket that may also be used to access or purchase an on-line lottery or promotional game.

2. Description of the Related Art

Scratch-off or instant win lottery tickets have been a staple of the lottery industry for decades. They have been enjoyed by billions of players over the world for years. Innovations in instant win ticket game design have sustained the product and allowed for growth. However, recently the instant win lottery ticket market sales increases have become relatively flat. One method of combating this undesirable trend is to produce higher payout instant win tickets. Most lottery jurisdictions regulate payout percentages by charter and therefore cannot utilize higher payout tickets as a means of increasing sales.

It is therefore desirable to develop a new methodology of marketing instant win lottery tickets where the player perceives added value independent of increases in payout percentages. It is to such a system and methodology the present invention is primarily directed.

SUMMARY OF THE INVENTION

The novel play style and game ticket of the present invention provides the opportunity to use an instant win scratch-off style game ticket for providing an on-line ticket with predetermined game entry indicia as a prize in the scratch game, or for use in up-selling on-line games in association with the sale of the known types of scratch ticket games.

In one embodiment, there is disclosed a method of implementing a secondary lottery game with a first instant lottery game in an instant lottery game. The method includes issuing an instant lottery ticket having a first instant lottery game to a player, if the first instant win lottery game is a winner, awarding a first prize the player, determining if the player is entitled to receive an entry to a secondary lottery game with predetermined secondary lottery game indicia based on the first instant win lottery game, entering the player in the secondary lottery game to the player if the player is entitled, determining if the player is a winner in the secondary lottery game, and awarding a second prize to the player if the player is a winner in the secondary lottery game.

In another embodiment, there is provided a ticket for an instant lottery game. The ticket includes a substrate, a set of player indicia placed on the top of the substrate and covered by a removable material, a set of instant lottery game indicia placed on the top of the substrate and covered by the removable material, and a bonus indicia placed on the top of the substrate and covered by the removable material. The bonus indicia indicating if a player is eligible for entry into a secondary lottery game with predetermined secondary lottery

2

game indicia. If the set of player indicia matches the set of game indicia according to a predefined criteria, then a pre-defined prize is awarded to a player. If the bonus indicia indicates entry into a secondary lottery game, the player is entered into the secondary lottery game.

Other objects, features, and advantages of the present invention will become apparent after review of the Brief Description Of The Drawings, Detailed Description Of The Invention, and Claims.

BRIEF DESCRIPTION OF THE DRAWINGS

FIG. 1 is an illustration of a game ticket of the present invention on which the scratch off layer of the ticket has not yet been removed.

FIG. 2 is an illustration of the ticket of FIG. 1 with the scratch off layer removed and which does not provide an on-line ticket as a game prize.

FIG. 3 is an illustration of an alternate embodiment of the ticket of FIG. 1 with the scratch off layer removed that does provide an on-line ticket as a game prize with a set for predetermined numbers for entry into the on-line game.

FIG. 4 is an illustration of a second game ticket of the present invention on which the scratch off layer of the ticket has not yet been removed.

FIG. 5 is an illustration of the ticket of FIG. 4 with the scratch off layer removed and which wins an on-line ticket as a game prize with the indicated numbers as entries.

FIG. 6 is an illustration of the ticket of FIG. 4 with the scratch off layer removed and which wins a game prize.

FIG. 7 is an illustration of a process for playing a lottery game according to the invention.

DETAILED DESCRIPTION OF THE INVENTION

Referring now to the drawings, information programmed and printed on a scratch-off lottery or promotional game ticket can be read by a lottery terminal. Based on the information contained in the scratch ticket and its unique barcode, the lottery terminal can award and generate a ticket for a separate online game such as Lotto, a Pick 3 game, or other terminal based games.

FIG. 1 illustrates one instant lottery ticket 100 according to the invention. The instant lottery ticket 100 is composed of a substrate of generally paper or other suitable materials. The instant lottery ticket 100 has two areas: theme area 102 and play area 104. The instant lottery ticket 100 generally carries a theme, which may be a sport game, auto racing, etc. The instant lottery ticket 100 is shown with a Chinese fortune cookie theme and basic instructions in its theme area 102. The play area 104 generally includes game information covered by a removable material. The game information is printed on the substrate and covered by latex or other suitable removable materials.

In one embodiment illustrated in FIG. 2, the game information in the "Fortune Cookie" ticket 200 has been uncovered. The game information includes a pair of LUCKY NUMBERS 202, a lucky fortune 204, a plurality of player numbers (YOUR NUMBERS) 206, and a plurality of prizes 208. The lucky fortune 204 will contain either a fortune or six "lucky numbers." For tickets that contain "lucky fortune numbers," the player, besides winning prizes if there is a match between the LUCKY NUMBERS 202 and player number 206, can redeem the scratch ticket 200 for a Lotto ticket, referring here to as an on-line lottery or promotional game, with the numbers to be played as marked on the scratch ticket. In the example of FIG. 2, the LUCKY NUMBERS 206 are six

and fifteen and player numbers are six, eleven, twenty, eight, fourteen, one, eighteen, twelve, seven, and ten. There is a match on number six and the prize associated with number six is twenty (\$20) dollars. The lucky fortune 204 reveals a fortune. So the ticket 200 entitles the player to win twenty dollars. If the LUCKY NUMBERS 206 were fourteen and fifteen, the player can redeem the ticket 200 for another ticket.

FIG. 3 illustrates a ticket 300 similar to the ticket 200 except that the lucky fortune 304 reveals a set of lucky fortune numbers as predetermined game indicia for entry into the on-line lottery. Besides redeeming the ticket 300 for twenty dollar prize for matching number six, the player may also redeem the ticket 300 for a terminal based lottery ticket, such as Lotto. The Lotto ticket will contain the lucky fortune numbers shown on FIG. 3. Once redeemed, the player will receive a Lotto ticket with the numbers, 12, 36, 4, 15, 22, and 9 entered into the next on-line Lotto game drawing.

In other embodiments of the invention, the theme may include "Instant Pick 3" or "Instant Lotto" type games, for example. In addition to a regular play area dedicated to playing a scratch-off lottery ticket, there may be something that makes the numbers "live." For example, "Your Numbers" on a ticket might be 3-4-6, i.e. the predetermined on-line game indicia. While there may not be a match between the "Your Numbers" and numbers printed in the scratch-off version, there is a bonus area and if the bonus area reveals a winner, "Your Numbers" on the ticket then become "live" and can be redeemed for an actual Pick 3 ticket with numbers 3-4-6 shown in the drawings. A separate ticket for entry into the secondary lottery game can also be issued by a ticket vending machine, such ticket printing machines being well known in the art.

FIG. 4 illustrates another instant lottery ticket 400 according to another embodiment of the invention. The theme for this embodiment is "Pick 3" and three numbers 402 are assigned to this lottery ticket 400. The player is provided with four games, which means four opportunities to win. The instant lottery ticket 400 also provides four "bonus" winning chances to the player. Though "Pick 3" and four games are provided with the instant lottery ticket shown in FIG. 4, those skilled in the art will appreciate other games and different winning opportunities may be provided with an instant lottery ticket.

FIG. 5 illustrates an instant lottery ticket of FIG. 4 with game information uncovered. The "Pick 3" numbers are "259," and four game numbers for the player are "187," "367," "348," and "671." The player did not win anything from the "Pick 3." However, from the bonus area, an "ENTRY" is shown beside "348" and the player is then entitled to win an on-line "Pick 3" ticket with numbers "348" for the next drawing.

FIG. 6 illustrates another instant lottery ticket of FIG. 4 with game information uncovered. The "Pick 3" numbers are "259," and four game numbers for the player are "189," "367," "348," and "671." There is a match on the third digit in game 1; therefore the player is entitled \$1. However, because there is a special symbol in the bonus area, the prize for the player is doubled.

FIG. 7 illustrates a process 700 for playing an instant lottery game according to the invention. The player purchases an instant lottery ticket from a retailer of lottery tickets, step 702, and scratch off the removable material to reveal the game information, step 704. By removing the removable material, the player can verify whether he is winner of an instant game, step 706. The information can be captured from the ticket by scanning means or other data collection as known in the art. If he is a winner, he can redeem the ticket for the prize with the

Lottery Authority, step 708. Besides being an instant game winner, the player may also be a winner for a secondary game ticket, step 710. If he is a winner for a secondary game ticket, the player can redeem the instant lottery ticket for a ticket for the secondary game, step 712, having the predetermined game indicia as described above. After he receives the ticket for the secondary lottery game, he can check whether he is a winner at the next drawing of the secondary lottery game, step 714. If he is a winner for the secondary lottery game, he can receive the prize for the secondary lottery game from the Lottery Authority. Thus, according to the present invention, the player has the chance to winning a secondary lottery game with the purchase of an instant lottery game.

The same concept works for Lotto, Cash Lotto, or any other terminal based game. Although several preferred embodiments of the invention have been disclosed in the foregoing specification, it is understood by those skilled in the art that many modifications and other embodiments of the invention will come to mind to which the invention pertains, having the benefit of the teaching presented in the foregoing description and associated drawings. It is thus understood that the invention is not limited to the specific embodiments disclosed herein, and that many modifications and other embodiments of the inventions are intended to be included within the scope of the appended claims. Moreover, although specific terms are employed herein, as well as in the claims, they are used in a generic and descriptive sense only, and not for the purposes of limiting the described invention.

In the context of FIG. 7, certain steps of the method may be implemented, for example, by operating a computer to execute a sequence of machine-readable instructions. The instructions can reside in various types of signal-bearing or data storage primary, secondary, or tertiary media. The media may comprise, for example, RAM (not shown) accessible by, or residing within, the components of the wireless network. Whether contained in RAM, a diskette, or other secondary storage media, the instructions may be stored on a variety of machine-readable data storage media, such as DASD storage (e.g., a conventional "hard drive" or a RAID array), magnetic tape, electronic read-only memory (e.g., ROM, EPROM, or EEPROM), flash memory cards, an optical storage device (e.g. CD-ROM, WORM, DVD, digital optical tape), paper "punch" cards, or other suitable data storage media including digital and analog transmission media.

While the invention has been particularly shown and described with reference to one embodiment thereof, it will be understood by those skilled in the art that various changes in form and detail may be made without departing from the spirit and scope of the present invention as set forth in the following claims. Though the method in FIG. 7 is illustrated in sequential steps, those skilled in the art will appreciate the different sequences may also be used to implement the invention. Furthermore, although elements of the invention may be described or claimed in the singular, the plural is contemplated unless limitation to the singular is explicitly stated.

What is claimed is:

1. A method of implementing a secondary lottery game with a first instant lottery game in an instant lottery game ticket, comprising the steps of:
issuing an instant lottery game ticket having a first instant lottery game to a player, the instant lottery ticket including a hidden potential entry to a secondary lottery game that is played by issuing a separate lottery game ticket to a player;

5

playing the first instant win lottery game embodied by the instant lottery game ticket and if the first instant win lottery game is a winner, awarding a first prize to the player;

revealing the potential entry to a secondary lottery game on the instant lottery game ticket;

determining if the player is entitled to receive an entry to the secondary lottery game based on indicia in the revealed potential entry to the secondary lottery game;

if the player is entitled, entering the player in the secondary lottery game by issuing a separate lottery ticket having predetermined game indicia for play in the secondary lottery game, the game indicia for the secondary lottery game provided by the revealed potential entry to the secondary lottery game on the instant lottery game ticket;

5

determining if the player is a winner in the secondary lottery game; and

awarding a second prize to the player if the player is a winner in the secondary lottery game.

2. The method as in claim **1**, wherein the player is entitled to entry in the secondary lottery game based solely on the revealed potential entry to the secondary lottery game without regard to results of the first instant win lottery game.

3. The method as in claim **1**, wherein for entry in the secondary lottery game, the first instant win lottery game must be a winning game for the player.
